UNITED STATES PATENT OFFICE.

GEORGE W. BINGHAM, OF GREAT FALLS, MONTANA.

SHUTTER-WORKER.

SPECIFICATION forming part of Letters Patent No. 599,053, dated February 15, 1898.

Application filed June 18, 1897. Serial No. 641,284. (No model.)

To all whom it may concern:

Be it known that I, GEORGE W. BINGHAM, of Great Falls, Cascade county, Montana, have invented certain new and useful Improvements in Shutter-Workers; and I do hereby declare the following to be a full, clear, and exact description of the invention, such as will enable others skilled in the art to which it pertains to make and use the same.

10 My invention relates to so-called "shutter workers and locks combined;" and it consists in the peculiar construction, combination, and arrangement of parts hereinafter more fully described.

15 In the drawings, Figure I is a plan view of a shutter worker and lock combined embodying my invention, showing the device in position when the shutter is closed and locked. Fig. II is a view in side elevation of the apparatus or device, showing more clearly the arrangement of the parts and their coöperation. Fig. III is a view showing the position of the parts when the shutter is locked when open.

20 A represents a portion of a window-casing. B represents a shutter suitably hinged to said casing at its upper portion.

C represents a plate, to the lower end of which is secured a pintle D, said pintle D extending out from the plate C and being preferably formed integral therewith.

25 E represents a so-called "spud," which is also secured to the lower end of plate C and preferably formed integral with it. The function of the spud E is to engage in a hole formed in the casing, said hole being of such diameter as that the spud E may be easily driven therein, thus holding the plate C more steady and preventing it from playing or loosening.

30 By using the spud E, I also obviate the necessity of using nails, screws, or like securing devices for securing the plate C to the frame or casing; but these devices may be used also in connection with the spud for securing the plate C to the casing, if it is so de-

35 sired. At the upper end of the plate C, I provide an opening c of such diameter as to accommodate a hub F and allow said hub to freely revolve or oscillate therein. To the 40 outer end of hub F is secured an arm F', the arm F' being so secured to hub F as to move with it. To the lower end of arm F' and pref-

erably formed integral with it is a rack or gear F², the teeth of which engage a segmental gear G, which forms the female portion of the lower hinge of the shutter and operates upon the pintle D. Extending from the segmental gear G is a bracket or arm G', which is provided with means for securely attaching it to the shutter B. This means may be bolts, screws, or analogous devices. Engaging the hub F and preferably adjustably secured therein is a spindle H, the length of which is determined by the depth of the casing, it being necessary that this spindle 8, after engaging the hub F in such a manner as to operate it, should extend inward and through the casing of the window-frame far enough to allow of the attachment of an operating-lever J, the operating-lever J being attached to the spindle H either in the manner shown in Fig. II or in any other suitable manner so as to operate said spindle.

The construction of my device for holding or locking the shutter in open or closed position is clearly shown in Fig. II of the drawings, wherein it will be seen that I provide the rack or gear F² between its ends with teeth f f', which are adapted to engage and mesh with the teeth g g g of the segmental gear G. I have shown and described but three of these teeth, but do not mean by this to limit myself to this number, inasmuch as this may be varied as desired or found convenient. At the outer end of the rack or gear F², I provide inclines f' f'', one on either end. These inclines f' f'' are adapted to register with and engage coöperating inclines g' g'', formed on the segmental gear G, and, as illustrated in Fig. I, after the shutter has been closed the two inclines f' g' engage and are tightened by means of a lever J, coöperating through the spindle H, hub F, and arm F' to move the rack or gear F², thus bringing the shutter up tight or close to the engaging parts of the casing, holding it there and keeping it from rattling or from being opened.

When the shutter is opened, as illustrated in Fig. I, it will be noticed that the inclines f'' on the rack F² will engage the incline g'' on the segment G, and as the rack or gear F² is moved the inclines will engage more closely, and thus the shutter is locked in open position.

It will be perceived that it is only necessary

to give to the lever J a partial revolution in order to operate the rack or gear F², and thus either open or close the shutter. It will also be noticed that by means of the incline f' g' and the incline f² g² after the shutter has been closed or opened it is securely locked in either position and prevented from rattling, as in ordinary devices of this kind.

What I claim is—

- 10 1. In a combined shutter worker and lock, the combination with the gear secured to the shutter, of a coöperating rack or gear operated from the interior of the window-casing, said gear and said rack having coöperating inclines, which engage for the purpose of locking the shutter, either in open or closed position, substantially as shown and described.
- 15 2. In a combined shutter worker and lock, the combination with the segmental gear secured to the shutter and forming the female portion of the lower hinge of the shutter, a suitable pintle upon which said segmental gear operates and a rack coöperating with said segmental gear for the purpose of oper-

ating the shutter, said rack being provided upon its ends with inclined surfaces which co-operate with inclines on the segmental gear for the purpose of locking the shutter either in open or closed position, substantially as and for the purpose described.

3. In a combined shutter worker and lock, the combination with the segmental gear secured to said shutter and revolving around a pintle suitably secured to the casing, of a rack coöperating with said segmental gear, said rack being located at the lower end of an arm, the upper end of said arm being secured to a suitable spindle, and through said spindle operated by means of a lever on the interior of the window-casing, substantially as and for the purpose shown and described.

In testimony whereof I sign this specification, in the presence of two witnesses, this 9th day of June, 1897.

GEORGE W. BINGHAM.
